UNITED STATES PATENT OFFICE

PIETER DANIEL VAN ESSEN, OF THE HAGUE, NETHERLANDS

PROJECTILE

Application filed May 15, 1924. Serial No. 713,513.

The use of trench mortars, infantry howitzers and similar articles of ordnance, combining the features of extreme mobility and the ability to fire high capacity projectiles at low range, have introduced new conditions in the supply of ordnance material suitable for this purpose. The chief requirements in regard to projectiles adapted for use in ordnance of this description is a maximum explosive capacity compatible with light weight and low calibre. Owing to the comparatively small calibre of trench mortars, this requirement involves the use of thin walled containers and projectiles of extended length. At high angles of incidence, and fused with instantaneous impact fuses, projectiles of extended length present certain advantages in that their zone of dispersion on fragmentation is a maximum, owing to the rearward protrusion from the ground of the main portion of the detonating charge, at the moment of impact. In this manner the localizing influence on the effect of detonation, due to irregularities in the ground is to a great extent overcome.

The difficulty hitherto has been to attain these advantages without unduly increasing the length of bore of the mortar and in consequence its weight. Furthermore, it has not been found practicable to reduce the thickness of the containing walls of the projectile, so as to increase their loading capacity, beyond well defined limits, dependent on the powder pressures in the gun and their distribution on the base or the rearward portion of the projectile.

To meet these requirements I have invented a projectile of such shape that the chamber pressure in the gun may be applied to a substantially large surface thereof, thus obviating the rearward thickening of the projectile walls customary in a projectile of normal design.

Another object of my invention is to provide a projectile adapted to be fired effectively under wide variations in the angle of elevation, without relying on its rotation about its axis to retain its position along the trajectory. Experience has shown that at high firing elevations rotating projectiles

drift out of their normal position tangential to the trajectory; this deviation impairs the proper functioning of direct impact fuses and also results in a deepened dispersion zone and loss of concentration on the objective. The use of wind vanes, as a means of correction, is effective only at the expense of the remaining energy of the projectile. In the case of projectiles having no initial rotation, for example, those fired from smooth bore guns, the conditions are still more difficult. While admitting the virtues of having the center of gravity as far forward as possible, and the stabilizing influence of wind vanes and similar contrivances, a further disturbing factor is introduced, viz: the influence of gas pressure immediately after the gas checking portion of the projectile has left the muzzle of the gun. Said pressure may cause a deviation of the axis of the projectile from its proper trajectory, which is the more aggravated by the fact that the projectile is not rotating. By my method of construction, I provide a projectile, substantially non-rotatable about its axis, having the known advantages of a forwardly placed center of gravity and corrective wind vanes, but by tapering the body of the projectile rearwardly and also providing centering means at the rear of said tapered body, I effect a gradual release of gas pressure, while continuing to guide or center my projectile until said release has been substantially effected. By these means I am able to obtain accurate and effective firing even at high angles of elevation, and substantially reduce the depth of dispersion usual in ordnance of this type.

A further object of my invention is to provide a projectile, the firing of which from the gun will not be disclosed by a highly luminous flash; similarly I aim to reduce the report emitted on gun fire so that the exact position of the battery shall not be disclosed to the enemy.

A further object of my invention is to secure even fragmentation of the projectile walls on detonation of the charge and their projection or dispersion at high velocity over a wide area.

In the attached drawing, I show in Fig. 1 a longitudinal section of my projectile, in Fig. 2 a side elevation and in Fig. 3 a rear end elevation.

In Fig. 1 of the drawing, I show a projectile consisting of a short ogival head A, adapted to receive an impact fuse B of known design, and having a cavity C to be filled with a high explosive. Rearwardly the head A is reduced as to its diameter and suitably threaded at D. I show a hollow explosive containing body E, tapered rearwardly, having a forward portion adapted to engage with the rearward portion D of the head A, and having a rearward portion adapted to engage with the forward portion F of the tail piece G. Said tail piece G is of hollow construction and is tapered externally from the diameter of the rearward extremity of the body E. Cast integrally with the tail piece G I show four wings or vanes H, set longitudinally and at right angles to each other, in thickness slightly tapering outwardly, bevelled rearwardly, and blended forwardly to a knife edge. In the preferred form, for projectiles adapted for use in breech loading guns, said vanes have bearing points J, formed by small lateral projections on the vanes. The diameter of the vanes over these projections is slightly greater than the smooth bore of the gun, so that said projections may be deformed to the dimensions of the bore when the projectile is forced home by the closing of a breech block. To permit of this deformation I provide a recess immediately in rear of each projection.

These projections, when deformed, serve to center the projectile in the gun during its travel up the bore. The maximum diameter of the projectile, at a point K immediately forward of the tapering body E, also acts as a centering band, as long as the head A is in the bore of the gun.

In the case of projectiles adapted for muzzle loading guns, the use of the deformable projections on the vanes are not essential, and the vanes may be so constructed that their peripheral edges fit slidably in the bore of the gun.

By this construction it is evident that the chamber pressure in the gun is applied to the major part of the external surface of the projectile, for example, the entire surface of the body E and the tail piece G, thus permitting the walls of the projectile to be appreciably thinner than would be possible by the conventional construction of a projectile, wherein the walls are of greater thickness rearwardly in order to withstand the setback of the forward sections of the projectile upon shock of gun discharge. As I have already explained, the centering or guiding of the projectile is provided by small projections on the wind vanes. Furthermore, the tapering of the body immediately in rear of the shoul-

dering portion of the projectile at its maximum diameter, affords a gradual release of the chamber pressure, as soon as said shoulering portion is free of the muzzle of the gun, and while the rearward portion of the projectile is still kept centered in the gun. In this manner, I avoid erratic deviation of the projectile at the commencement of its trajectory. These important advantages are attained, in addition to those known to result from the use of wind vanes and a center of gravity disposed as forwardly as possible. Furthermore, the profile of my projectile body is such as to avoid the formation on impact and detonation of any elongated fragments, but to attain an even fragmentation with a wide dispersion of the said fragments at high velocity.

From the foregoing, it will be apparent that I have devised a projectile suitable for a smooth bore gun in that the projectile is accurately centered in its loaded position as well as during its travel along the gun bore and the propellant pressure is gradually released as the projectile reaches the muzzle.

Having thus described the invention what I claim as new and desire to secure by Letters Patent is:

In a trench mortar projectile the combination of, a short ogival head blending rearwardly with a portion adapted to fit the muzzle of the mortar, a substantially elongated frusto-conical body portion attached rearwardly of the head, a conical tail portion having wind vanes extending to fit the muzzle of the mortar, all of said portions being chambered to receive explosive, and presenting in flight an extended stream line surface substantially uninterrupted except by the vanes extending therefrom.

In testimony whereof I hereunto affix my signature this 13th day of May, 1924.

PIETER DANIEL VAN ESEN.
